UNITED STATES PATENT OFFICE.

CHESTER A. BARNES, OF BLUE GRASS, IOWA.

HARROW SCRAPER.

Application filed November 16, 1923. Serial No. 675,225.

To all whom it may concern:

Be it known that I, CHESTER A. BARNES, a citizen of the United States, residing at Blue Grass, in the county of Scott and State 5 of Iowa, have invented certain new and useful Improvements in a Harrow Scraper, of which the following is a specification.

This invention appertains to farming implements and the primary object of the 10 invention is to provide a novel scraper or cleaner for the disks of disk-harrows, whereby the said disks can be expeditiously cleaned.

Another prime object of the invention is 15 the provision of an improved scraper attachment for disk-harrows which can be associated with any preferred type of disk-harrow, the attachment embodying novel resilient means for normally urging the 20 scraping blades simultaneously into scraping position with the faces of the disks for effectively scraping clods of earth, mud and the like therefrom.

Another prime object of the invention is 25 the provision of means for automatically urging the scraper blades of the attachment into engagement with the active face of the disks, thereby eliminating the necessity of manually urging the scraper blades into 30 engagement with the disk by the use of a foot pedal or the like.

A further object of the invention is the 35 provision of a novel scraper attachment for disk-harrows embodying a supporting frame for connection with the harrow, a plurality of scraper blade carrying arms supported by the frame, novel means for connecting the arms together, novel means for urging the arms in a predetermined direction for holding the scraper blades in operative 40 relation to the disks of the harrow, and novel manually operated means for moving the scraper blades from out of operative position in relation to the disks.

45 A further object of the invention is the provision of novel means for mounting the scraper blade carrying arms on the frame, whereby accidental twisting movement of the arms will be eliminated.

50 A further object of the invention is the provision of novel means for connecting the scraper blade supporting arms with the bar utilized for connecting all of the arms together, whereby the arms can be adjusted

independently of one another to compensate 55 for uneven wear on the scraper blades.

A still further object of the invention is to provide an improved scraper attachment for disk-harrows of the above character, which will be durable and efficient in use, 60 one that will be simple and easy to manufacture and one which can be placed upon the market and incorporated with a disk-harrow at a minimum cost.

With these and other objects in view, 65 the invention consists in the novel construction, arrangement and formation of parts, as will be hereinafter more specifically described, claimed and illustrated in the accompanying drawings, in which drawings: 70

Figure 1 is a top plan view of a harrow showing the improved scraper attachment incorporated therewith.

Figure 2 is a side elevation of the harrow showing the improved attachment incorporated therewith. 75

Figure 3 is a front elevation of one gang of harrow disks showing the improved scraper attachment incorporated therewith, the frame being shown in section. 80

Figure 4 is an enlarged fragmentary rear elevation of a portion of the scraper attachment illustrating the manual means for moving the scraper blade carrying arms against the tension of the spring means and the 85 novel means for adjustably connecting each scraper blade carrying arm with the bar utilized for connecting all of said arms together, and

Figure 5 is a detail transverse section 90 taken on the line 5—5 of Figure 4 illustrating the novel means for connecting one of the scraper blade carrying arms with said frame.

Referring to the drawings in detail, 95 wherein similar reference characters designate corresponding parts throughout the several views, the letter A generally indicates a harrow of the disk type and B the improved scraper attachment therefor. 100

The disk-harrow A can be of any desired make or construction and has been shown simply to illustrate the use of the improved scraper. The harrow A as shown includes the frame 10 preferably formed of angle 105 iron having the caster wheels 11 connected with the forward end thereof. Any preferred type of draft beam 12 can be connect-

ed with the caster wheels 11 so as to permit the drawing of the disk-harrow over a field. Either draft animals, or tractor can be utilized for pulling the said harrow. The rear 5 end of the frame 10 supports gangs 13 of harrow disks and as shown the frame supports rear bearings 14 for receiving the axles 15 upon which the disks 16 of the gangs are mounted. The various details of construction 10 of the harrow has not been gone into, in view of the fact that the invention resides, as heretofore stated, in the improved attachment B. However, the harrow A is provided with means 17 for permitting the adjustment of the harrow gangs 13 relative to the frame, and the frame supports a suitable seat 18 located directly between the gangs 13 of the harrow disks.

For a disk-harrow embodying two gangs 20 of disks the improved scraper attachment B comprises left and right-hand sections 19 and 20. These sections 19 and 20 are constructed identically the same and therefore the description of one is deemed sufficient 25 for both.

Each section embodies a supporting frame 21 preferably formed of angle iron and each frame includes the spaced transversely extending angle bars 22 which are connected 30 at their outer ends by means of a short angle bar 23.

Arranged in spaced relation to the rear angle bar 22 is a bar 24 which can be formed of strap iron or the like. Each frame 21 35 supports depending brackets 25 which are bolted or otherwise secured as at 26 to the bearings 14. This holds each frame above its gang of disk harrows. An arm 27 is provided for each disk 16 and these arms 40 are disposed between the rear angle bar 22 and the bar 24 in spaced relation, as clearly shown in the drawings. Each arm 27 has secured thereto in any preferred way at a point intermediate its ends, a block 28 which 45 is connected through the medium of a pivot pin 29 to the rear angle bar 22 and the bar 24. The lower ends of the arms 27 have riveted or otherwise secured thereto the scraper blades 30 which are curved to conform to the configuration of the disks 16. These blades are of a sufficient length to extend from the axial center of each disk to the periphery thereof. It is preferred to slightly twist the lower end of each arm 27 50 so as to place the scraping blade at an angle with the curve of the disks. The arms extend an appreciable distance above the frame 21 so that a sufficient throw and leverage can be given to each arm. Arranged above the 55 arms 27 is a connecting bar 31 which supports depending relatively short adjustable bars 32. These bars 32 are held in an adjusted position on the connecting bar 31 through the medium of U-shaped clamps 33 60 which embrace the bar, and flanges of the

U-shaped clamps are slotted or notched to receive the vertical bars 32. Each bar 32 is provided with a vertically extending slot 34 while the connecting bar 31 is provided with transversely extending slots 35. An adjusting bolt 36 is passed through the slots 34 and 35 and a suitable nut 37 is placed on the threaded end thereof. It is obvious that by loosening the nut and bolt, each vertical bar can be adjusted both in a vertical and 70 a horizontal plane, the purpose of which, will be hereinabove more fully described. The upper terminals of the arms 27 are bifurcated to receive the lower ends of the vertical bars 32 and the bifurcated ends of the arms are rolled to provide eyes 37' for receiving connecting bolts 38 which extend through the lower ends of said vertical bars 32. Now by adjusting the vertical bar 32 and the clamp 33, each scraper blade 30 can 85 be adjusted relative to its own disk, which is essential for compensating for wear thereon.

By moving the connecting bar 31 all of the arms 27 are operated, thereby bringing the scraper blades into or out of operative position relative to their disks 16 according to the direction of movement of the connecting bar. A relatively heavy contractile coil spring 40 is utilized for urging the connecting bar inwardly, so as to normally hold the scraper blades in active position relative to the disks. One end of the spring 40 is connected to a suitable bolt 41 carried by the connecting bar 31 adjacent to its inner end, 90 while the opposite end of the spring is connected to the inner end of an adjusting screw 42 carried by the outer longitudinal angle bar 23. It is obvious that by adjusting the screw 42, the tension of the spring 40 can be 95 regulated.

When it is desired to hold the scraper blade out of operative position relative to the disks or to adjust the position of the scraper blades relative to the disks a main 110 adjusting screw 43 is actuated. This main adjusting screw 43 is carried by a suitable block 44 secured to the inner end of the connecting bar 31 and in order to facilitate the turning of this screw a hand wheel 45 is 115 rigidly secured to the upper end thereof. The lower end of the main adjusting screw 43 is adapted to impinge against the rear angle bar 22 and it is obvious that by rotating the screw so as to keep the same downward that the connecting bar can be lifted and the arms swung against the tension of the spring 40.

From the foregoing description, it can be seen that I have provided an exceptionally 125 simple and durable scraper for harrow disks, which will effectively accomplish the purpose intended and eliminate the difficulty heretofore contingent with the use of scrapers now on the market.

Changes in details may be made without departing from the spirit or the scope of this invention.

What I claim as new is:

- 5 1. The combination with a harrow including a gang of harrow disks, of a scraper attachment for the harrow including a horizontally disposed frame arranged above the gang of harrow disks, an arm pivotally secured to the frame for each disk, a scraper blade secured to the lower end of each arm for engaging the disk, a connecting bar arranged above the frame, means adjustably connecting each arm with the connecting bar, resilient means for normally urging the connecting bar in one direction for moving the scraper blade in an operative scraping position relative to the harrow disks, and manual means for moving the connecting bar in the opposite direction against said spring means.
- 10 2. The combination with a harrow including a gang of harrow disks, a frame, bearings connecting the gang of harrow disks to the frame, of a scraper attachment for the harrow including a supporting frame arranged above the gang of harrow disks, depending brackets carried by the supporting frame secured to said bearings, a plurality of pivoted arms secured to the supporting frame at a point intermediate their ends, a blade carried by the lower end of each arm for engaging a harrow disk, a connecting bar, vertically extending attaching bars pivotally connected to the upper end of each arm, means adjustably connecting vertical bars to the connecting bar, and a contractile coil spring connected to the supporting frame and connecting bar, and a manually operated screw for adjusting said

connecting bar in a direction against the tension of said spring.

3. The combination with a harrow including a gang of harrow disks, of a scraper attachment for the harrow including a frame, a plurality of arms pivotally secured intermediate their ends to the frame, scraper blades carried by the lower ends of the arms for the harrow disks, a connecting bar arranged above the upper ends of the arms, vertically extending bars pivotally connected to the upper ends of the arms, said vertically extending bars being provided with vertically extending slots, the connecting bar being provided with spaced horizontally disposed slots, U-shaped clamps straddling said connecting bar and slidably receiving the vertical bars, and adjusting bolts extending through the connecting bar, clamps and vertically disposed bars, as and for the purpose specified.

4. A scraper attachment comprising a frame, a plurality of pivoted arms secured to the frame, a connecting bar, means adjustably connecting each arm to the connecting bar, a longitudinally curved scraper blade carried by the lower end of each arm, resilient means for normally urging the connecting bar in one direction, and a manually operated screw carried by the connecting bar and for engaging said frame for moving said connecting bar in a direction opposite to the pull of said spring.

In testimony whereof I affix my signature in presence of two witnesses.

CHESTER A. BARNES.
